UNITED STATES PATENT OFFICE.

ALBERT F. GRISWOLD, OF ERIE, PENNSYLVANIA.

FACING FOR SAW-MILL HEAD-BLOCKS.

SPECIFICATION forming part of Letters Patent No. 281,762, dated July 24, 1883.

Application filed January 6, 1883. (No model.)

To all whom it may concern:

Be it known that I, ALBERT F. GRISWOLD, a citizen of the United States, residing at Erie, in the county of Erie and State of Pennsylvania, have invented certain new and useful Improvements in Facings for Saw-Mill Head-Blocks; and I do hereby declare the following to be a full, clear, and exact description of the invention, such as will enable others skilled in the art to which it appertains to make and use the same.

This invention relates to the construction of saw-mill head-blocks; and it consists in providing a steel facing for the nose and face of the block, as hereinafter specified.

In the operation of sawing, the log, when it is set forward for a new cut by the action of the knees, is slid on the face of the block, and the result is that it wears away the face very rapidly, and so it has been found necessary to face the face of the block with steel. Such facings have been laid from the point of the nose back along the face of the block. Two difficulties have been found to exist in this construction—viz., the end of the facing at the point of the nose is very apt to get caught by an on-coming log, and get bent up, and especially so when the facing becomes worn thin at that point. The other defect is that when the facing becomes worn thin at the nose end of the block, as it does to a far greater extent than at points farther back, entire new facing-plates are required; although the rear parts of the plates may be very little worn, there being no provision made for reversing the plates. To remedy these defects is the object of the construction here shown.

The invention is illustrated in the accompanying drawings as follows: Figure 1 is a side elevation of a head-block and knee, and shows my improved facing in place. Fig. 2 is a front elevation of the nose of the block, and shows my facing in place. Fig. 3 is a perspective view of the facings detached from the block.

A is the block; a, the face of the block. B is the plain facing-plate; B', the nose facing-piece, and C the knee. The construction will be readily understood from the illustration.

The facings are in two parts, the plate B and 50 the nose-piece B'. They are held in place on

the block by bolts D D, &c., which have their heads countersunk in the holes d d in the facings. The plates B have the holes d so arranged that they can be placed in the same position on the blocks either end foremost, 55 and hence can be reversed when desired. The nose-pieces B' are made with a lip or back-lap, b, which reaches down under the nose of the block, and is there secured by a screw. The top or face part of the piece B' is secured 60 by a bolt, D, and may also have screws, as shown, nearer the point. The most wear upon the facings is at the point of the nose, and gradually diminishes toward the rear of the block. Hence it is that the nose-pieces wear 65 out first, and when constructed as shown, they can be replaced with new ones, when desired, and when so replaced the plates B are reversed end for end, and the unworn end of the plate B will correspond in thickness with 70 the end of the new nose-piece. Aside from the purposes of this construction above named the facing of the nose of the block is very important, in that it prevents the nose becoming mutilated by coming in contact with the log- 75 turning apparatus, which is constantly occurring, and often results in breaking and chipping off the end of the nose so much that the block is unable to sustain the last board in the cant. So far as this latter purpose is concerned the facing-piece and nose-piece may all be one piece of metal.

What I claim as new is—

1. A facing-plate for saw-mill head-blocks, having thereon a lip or back lap, b, which reaches over and below the nose of the block, substantially as and for the purposes mentioned.

2. A facing for saw-mill head-blocks, consisting of the two parts B and B', of which the 90 part B is constructed to be reversed, as described, and the part B' is made to reach over and below the nose of the block, as shown and for the purposes mentioned.

In testimony whereof I affix my signature 95 in presence of two witnesses.

ALBERT F. GRISWOLD.
